UNITED STATES PATENT OFFICE.

LEONARDO SPREMULLI AND ARNALDO MANUPPELLI, OF ELLSWORTH, PENNSYLVANIA,
ASSIGNORS OF ONE-THIRD TO ANTHONY MARCELLO COSTA, OF BENTLEYVILLE,
PENNSYLVANIA.

GARBAGE-CAN.

1,141,846.

Specification of Letters Patent. Patented June 1, 1915.

Application filed January 13, 1914. Serial No. 811,884. Renewed April 14, 1915. Serial No. 21,449.

To all whom it may concern:

Be it known that we, LEONARDO SPREMULLI and ARNALDO MANUPPELLI, subjects of the King of Italy, residing at Ellsworth, in the 5 county of Washington and State of Pennsylvania, have invented certain new and useful Improvements in Garbage-Cans; and we do hereby declare the following to be a full, clear, and exact description of the invention, 10 such as will enable others skilled in the art to which it appertains to make and use the same.

This invention relates to new and useful 15 improvements in garbage cans and resides in the provision of a novelly constructed can which is extremely sanitary and provided with means for disinfecting and deodorizing whereby objectionable smells are dispensed with.

20 Another important object of our invention is to provide a garbage can of the character described which employs a closure cap constructed in a novel manner so that a sponge or wad of suitably absorbent material containing a disinfectant and deodorizer may be supported within the cap in spaced relation to the garbage in the can.

Another important object of our invention 30 is to provide a closure cap of the character described which employs means for preventing garbage coming in contact with the disinfecting and deodorizing means and to provide a removable cap at the upper end of the closure cap whereby ready access to the 35 means for holding the disinfectant or deodorizer is had.

This invention aims to improve garbage cans of the character described so as to render them more practical, sanitary, strong 40 and durable, cheap to manufacture and more commercially desirable.

The above and additional objects are accomplished by such means as are illustrated in the accompanying drawings, described in 45 the following specification and then more particularly pointed out in the claim which is appended hereto and forms a part of this application.

With reference to the drawings, wherein 50 we have illustrated the preferred embodiment of our invention as it is reduced to practice, and throughout the several views of which similar reference numerals designate corresponding parts: Figure 1 is a vertical sectional view taken through our im-

proved garbage can showing the can in assembled position, and Fig. 2 is a top plan view of the can.

Referring to the drawing, the numeral 1 designates the body portion of the can which in the preferred form is cylindrical and constructed of some suitably light metal and provided with a concavo convex bottom wall 2.

A stand, designated 3 as an entirety and consisting of a concaved body plate 4 and supporting legs 5 which are preferably integral with the body plate 4, is adapted to receive the can so that the bottom wall 2 of the can is spaced from the ground and prevents rusting. The peripheries of the wall 2 and plate 4 are formed in flat horizontal bearing portions 6 which bear against each other and prevent falling or toppling of the can. 75

The upper portion of the body portion 1 is offset to provide a reduced neck portion 6^a and shoulder 7. A conical closure cap 8 having its inner edge bent inwardly and upwardly to form a U-shaped portion 9 is 80 adapted to seal the can or body portion 1 and is disposed with the U-shaped portion 9 in engagement with the shoulder 7. The U-shaped portion 9 provides for the disposal of the cap 8 and body portion 1 in flush relation to each other and provides a neat and secure fastening. 85

Mounted adjacent the apex portion of the conical closure cap 8 is a semi-spherical container 10 provided with a plurality of perforations 11 and a peripheral securing flange 12 that is disposed at right angles to the container 10. This flange 12 is bent downwardly and angularly at its outer edge and soldered or otherwise suitably secured to the inner curved face of the conical cap 8 as at 13. A sponge or wad of suitable absorbent material, not shown, is saturated with a disinfectant and is placed within the container 10. 90 95 100

Disposed below the container 10 within the cap 8 is a horizontally arranged perforated plate 14 that is soldered or otherwise suitably secured to the cap 8 as at 15. This plate 14 is arranged in spaced relation to the container 10 and to the reduced neck portion 6 of the body portion 1, so that garbage when placed in the body portion 1 is prevented coming in contact with the container 10. 105 110

An opening is formed in the apex portion of the conical closure cap 8 and is provided along its edges with an inwardly extending annular flange 16 that is screw threaded 5 upon its outer face to receive the screw threaded flange 17 carried by a closure cap 18. This cap 18 is provided with a suitable handle portion 19 and seals the opening in the main cap. It will be readily seen that 10 access to the container for the purpose of removing or placing the sponge saturated with disinfectant therein is readily permitted by the arrangement described.

It will be readily seen that the garbage can of our improved construction can be manufactured at a low cost and possesses many advantages over the old style of garbage cans inasmuch as sanitary conditions are had and objectionable odors are dispensed with.

20 In reduction to practice, we have found that the form of our invention, illustrated in the drawings and referred to in the above description, as the preferred embodiment, is 25 the most efficient and practical; yet realizing that the conditions concurrent with the adoption of our device will necessarily vary,

we desire to emphasize the fact that various minor changes in details of construction, proportion and arrangement of parts may 30 be resorted to, when required, without sacrificing any of the advantages of our invention, as defined in the appended claim.

What is claimed is:—

A garbage can comprising a cylindrical 35 body portion and a stand for supporting the can comprising a concaved body plate and a plurality of integral supporting legs whereby the can is spaced from the ground, said body portion having a convex bottom wall 40 and provided adjacent its periphery with a flat horizontal portion, said body plate having a flat horizontal portion adjacent its periphery adapted for engagement with the flat horizontal portion on the bottom wall of 45 said can whereby the can is prevented overturning relative to the stand.

In testimony whereof we affix our signatures in presence of two witnesses.

LEONARDO SPREMULLI.
ARNALDO MANUPPELLI.
